UNITED STATES PATENT OFFICE.

CHARLES F. SUTTER, OF VANLUE, OHIO.

RUNNER END OR CROOK FOR SLEDS.

1,121,950.

Specification of Letters Patent. Patented Dec. 22, 1914.

Application filed March 7, 1912. Serial No. 682,284.

To all whom it may concern:

Be it known that I, CHARLES F. SUTTER, citizen of the United States, residing at Vanlue, in the county of Hancock and State 5 of Ohio, have invented certain new and useful Improvements in Runner Ends or Crooks for Sleds, of which the following is a specification, reference being had therein to the accompanying drawing.

10 This invention relates to a runner end or "crook" for sleds and is designed more particularly for that type of sled known as a "mud boat".

The object of the invention is to provide 15 a crook which can be applied to the front end of a straight runner, thus enabling the runner to be made from a plank with a minimum of work and expense; further, to provide such a "crook" which will be very 20 strong and can be rigidly secured to the runner and to the upper structure of the sled.

In the accompanying drawings Figure 1 25 is a side elevation, partly in section, of a shoe or "crook" embodying my invention showing the same applied to the end of the runner; and Fig. 2 is a section taken transversely of the same.

In these drawings I have illustrated one 30 embodiment of my invention and have shown the "crook" as formed of a single piece of sheet metal which, in the present instance, is bent into the desired shape. It will be obvious, however, that the device 35 can be built up of more than one piece of metal or that it can be formed in other manners than by bending. It will be noted that the "crook" comprises a long curved body portion 1 having the shape which it is 40 desired to impart to the forward portion of the runner. This curved body portion is provided along each side with an upwardly extending flange 2 which gives strength to the "crook" and also prevents the accumulation 45 of mud or the like on the top of the runner. The rear portion of the "crook" is straight and the central portion thereof is adapted to extend beneath the adjacent portion 50 of the runner 4 and to be rigidly secured thereto. The width of the crook is substantially equal to the width of the runner and, consequently, the flanges at the sides of the crook will fit snugly against the sides of the runner and can be secured there-

to. Preferably, those portions of the flanges 55 at the rear end of the crook extend upwardly for a considerable distance to afford ample means for fastening the end of the crook to the runner. At its forward and upper end the crook is provided with a flat 60 portion 3 to receive the forward end of the frame members of the sled. As here shown this support is formed by bending the end portion of the body rearwardly so that the frame member can rest upon it and be 65 bolted thereto. The crook is also bent to form an upwardly extending longitudinal rib 5 which is disposed centrally between the flanges 2, and serves to materially 70 strengthen the article.

It will be apparent that by providing this metallic crook I am enabled to build a sled runner by combining a straight plank of timber with the crook, thereby eliminating the necessity of providing the end of the 75 beam or timber with the crook and not only saving a great deal of material and expense but greatly reducing the labor involved in building the runner. Mud sleds are usually built by the farmer who uses the same, and, 80 by the use of this crook which can be furnished at a low cost, the farmer can very quickly and very easily build his runners. Little or no mechanical skill is required and the difficulties which are encountered in giving the proper shape to the wooden runner 85 where the same is provided with a curved portion are entirely avoided.

While I have shown and described one embodiment of the invention it will be understood that this has been chosen for the purpose of illustration only and that I do not desire to be limited to the details of construction shown and described, for obvious modifications will occur to a person skilled 90 in the art.

Having thus fully described my invention, what I claim as new and desire to secure by Letters Patent, is:—

As an article of manufacture, a crook for 100 a sled runner formed from a single piece of sheet metal and comprising a body portion bent about a longitudinal axis to form a structure U-shaped in cross section to receive the end of the runner and to provide 105 strengthening flanges and guards at the lateral edges of said body portion, said body portion also having an inwardly bent part

to form an upwardly extending longitudinal rib arranged centrally between said flanges, the forward end portion of the runner being curved upwardly and having its 5 front end portion bent rearwardly to form a flat support for the frame member of the sled.

In testimony whereof, I affix my signature in presence of two witnesses.

CHARLES F. SUTTER.
